AIRSHIP

Serge Trey, Beachhurst, N. Y.

Application July 2, 1946, Serial No. 681,083

9 Claims. (Cl. 244—73)

1

The invention relates to airships and, more particularly, to airships the operation of which involves the use of artificially produced streams of air.

The main object of the invention is to create a propelling force by causing a stream of air to be discharged from the nose of the airship over its entire surface towards the trailing end of the craft. It is further an object of the invention to cause the emission of the discharged stream of air to proceed at substantially a right angle to the longitudinal axis of the craft from points along the extreme forward end of the nose, corresponding to the effect which in the case of an airplane is called energization of the boundary layer. The location of the points of emission and the direction of the discharge at right angles to the axis of the craft are essential to the requirement that the emitted air stream proceed tangentially to the nose of the airship. It is also an object of the invention to cause the craft to become inclined about any line perpendicular to the longitudinal axis of the airship by controlling the discharge of said airstream. A further object is to create another air stream discharged at or near the tail end of the craft to effect a reactive force of propulsion, in addition to the force effected by the stream of air discharged from the nose of the craft. Still another object is to straighten out the flow of air as it approaches the tail end of the airship in order to do away or, at least, reduce the tail end vortices. It is also an object of the invention to permit universal rotation of the tail end of the craft and to further control the inclination of the airship by controlling the discharge of said second stream of air. Other objects will become apparent from the specification which follows and from the accompanying drawing, in which

Figure 1 is a side elevation of an airship embodying the present invention, partly shown in cross section.

Figure 2 is a detail of the control mechanism for the discharge of air from the nose of the craft.

Figure 3 is a front view of the airship which is illustrated in Figure 1.

Referring to the figures in detail, 1 is the envelope of an airship embodying the present invention. Two engines are shown, one at 2 and another at 3. The engine 2 activates a blower 4. Outside air is admitted into the airship through the tube 5 attached to the housing 6. The air from the blower 4 is discharged through the annular opening 7. The discharge of the air

2

is controlled by a plurality of shutters 8 operated as is schematically shown in Figure 2. The mechanism for the operation of the shutters 8 is distributed around the tube 5. Six of such mechanisms are shown in the illustration. Each consists of two cylinders 15 and 18, in which travel the pistons 14 and 19 with their piston rods 13 and 20. Oil for the cylinders is supplied from the reservoir 33 through the pipes 17 and 16 which also connect the two cylinders 15 and 18. The piston rod 13 is connected through the linkage 12—13 with the operating handle 9 pivoted at 10 in the segmental detent 11. The piston rod 20 is connected to a shutter 8. The operation of this mechanism is self-explanatory and provides for selective operation of the shutters.

Coming now to the other end of the airship, the conical tail piece 26 is pivoted in a universal ball joint 25 attached to the main body of the airship, as by a rod 31 secured by the nut 32. At 21 is shown an entry for the outside air for the blower 22 activated by the engine 3. The conical tail piece 26 has a series of pins 27 by which its motion is operated to close the passage way 24 in any of the numerous available positions, thereby controlling the discharge of air from the blower 22 into the passage 23 and slot 24. The manipulation of the tail piece 27 is effected by cables 28 moving over rollers 29 and 30.

The air discharged through the annular opening 24 creates a reactive force of propulsion. The nature of this air jet is entirely different from the air jet discharged from the nose of the craft. The function of the latter is to improve the aerodynamic conditions on and around the airship, very much like the function of such air jets used in connection with airplanes. While the characters of the two air streams in the present case are different, they are complementary to one another and combine in jointly effecting propulsion of the airship. The additional function of the tail and jet in straightening out the end vortices adds to the efficiency of this method of propulsion.

There are many ways for admitting outside air into the airship, one of these other ways being illustrated in the entry 21, and, while I prefer the method disclosed for the entry through the tube 5 at the nose of the craft for the discharge of the nose air jet, I do not intend to limit the invention to this particular illustration on the point of entry of outside air. Nor need the entry for the nose jet be necessarily located at the nose. Also, the control of the discharge of air may be altered, both with regard to the use of shutters and with regard to the use of a plurality

of shutters. Thus, I may use a single shutter revoluble about the longitudinal axis of the ship and regulate the closures by revolving the single shutter. These and many other variations of several of the details of the structure are naturally implied, so long as they conform to the fundamental principles underlying the present invention.

I claim:

1. An airship provided with an entry into it of outside air, means for changing the entered outside air into a high velocity pressure stream, an annular opening at the nose of said airship for discharging said air stream tangentially over the entire leading surface of said airship, closures for controlling the flow of air through said annular opening, and means for operating said closures.
2. An airship provided with a tube for admitting outside air into the nose of the ship, means for changing the admitted air into a high velocity pressure stream, an annular opening on said nose disposed around said tube for discharging said air stream tangentially over the entire leading portion of the envelope of the airship, shutters distributed around said tube for controlling the flow of said air stream through said annular opening, and means for operating said shutters.
3. An airship provided with an entry into it of outside air, a blower for changing the admitted outside air into a high velocity pressure stream, an annular opening at the nose of the airship for discharging said air stream perpendicularly to the longitudinal axis of the ship and causing it to spread over the entire leading surface of the envelope of the ship, and means for inclining the airship by controlling the flow of said air stream through said annular opening.
4. An airship provided with an entry into it of outside air, means for changing the entered outside air into a high velocity pressure stream, an annular opening at the nose of said airship for discharging said air stream perpendicularly to the longitudinal axis of the airship and spreading it in close contact with the leading portion of the envelope and over the entire surface of said airship, closures for controlling the flow of air through said annular opening, and means for operating said closures.
5. An airship provided with a tube for admitting outside air into the nose of the ship, means for changing the admitted air into a high velocity pressure stream, an annular opening on said nose disposed around said tube for discharging said air stream perpendicularly to the longitudinal axis of the ship and spreading it over the envelope, shutters distributed around said tube

for controlling the flow of said air stream through said annular opening, and means for operating said shutters.

6. An airship provided with an entry into it of outside air, a blower for changing the entered outside air into a high velocity pressure stream, an annular opening at the nose of said airship for discharging said air stream tangentially over the entire leading surface of said airship, closures for controlling the flow of air through said annular opening, and means for selectively operating said closures.

7. An airship provided with a tube for admitting outside air into the nose of the ship, a blower for changing the admitted air into a high velocity pressure stream, an annular opening on said nose disposed around said tube for discharging said air stream tangentially over the entire leading portion of the envelope of the airship, shutters distributed around said tube for controlling the flow of said air stream through said annular opening, and means for selectively operating said shutters.

8. An airship provided with an entry into it of outside air, means for changing the entered air into a high velocity pressure stream, an annular opening at the nose of said airship for discharging said air stream perpendicularly to the longitudinal axis of the airship and spreading it in close contact with the entire leading portion of the envelope of said airship, closures for controlling the flow of air through said annular opening, and means for selectively operating said closures to control the altitude of said airship.

9. An airship providing for the entry into it of outside air, means for changing the admitted outside air into a high velocity pressure stream, an annular opening at the extreme forward end of the airship for discharging said air stream perpendicularly to the axis of the ship and spreading it over the surface of the ship in close contact with the leading portion of this surface, and means for inclining the airship by controlling the flow of the high pressure airstream through the annular opening.
